CLAIM

The ornamental design for a light bulb, as shown and described.

DESCRIPTION

FIG. 1 is a front, perspective view of the first embodiment of a light bulb showing our new design;

FIG. 2 is a rear view of the first embodiment of the light bulb;

FIG. 3 is a front view of the first embodiment of the light bulb;

FIG. 4 is a right view of the first embodiment of the light bulb;

FIG. 5 is a left view of the first embodiment of the light bulb;

FIG. 6 is a top plan view of the first embodiment of the light bulb;

FIG. 7 is a bottom plan view of the first embodiment of the light bulb;

FIG. 8 is a front, perspective view of the second embodiment of a light bulb showing our new design;

FIG. 9 is a rear view of the second embodiment of the light bulb;

FIG. 10 is a front view of the second embodiment of the light bulb;

FIG. 11 is a right view of the second embodiment of the light bulb;

FIG. 12 is a left view of the second embodiment of the light bulb;

FIG. 13 is a top plan view of the second embodiment of the light bulb; and,

FIG. 14 is a bottom plan view of the second embodiment of the light bulb.

(Continued)

The broken lines in the drawings are for illustrative purposes and represent environmental structure and unclaimed portions of the light bulb and therefore form no part of the claimed design.
